[57] CLAIM

The ornamental design for an automobile tire, as shown and described.

DESCRIPTION

FIG. 1 is a perspective view of the automobile tire, showing the new design;

FIG. 2 is a front view of the automobile tire, the rear view, top plan view and bottom plan view appearing the same as the front view;

FIG. 3 is a right-side view of the automobile tire;

FIG. 4 is a left-side view of the automobile tire;

FIG. 5 is an enlarged fragmentary front view, showing in enlargement a portion of FIG. 2; and,

FIG. 6 is a sectional view, taken on line 6—6 of FIG. 5.
